(57) **CLAIM**

The ornamental design for a chair as shown and described.

DESCRIPTION

FIG. 1 is a front view for a chair showing the new design thereof;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a fully assembled perspective view thereof;

FIG. 8 is a partially exploded perspective view thereof; and,

FIG. 9 is a fully exploded perspective view thereof.

Modular chair; the thin irregular lines on the surfaces of the claimed design show shading that defines the contours of the modular chair and do not reflect a particular surface ornamentation or material.

1 Claim, 9 Drawing Sheets
